AUXILIARY GAS LIFT FOR OIL WELLS

Horace Justin Arnall, Clay City, Ill.

Application July 5, 1950, Serial No. 172,061

3 Claims. (Cl. 103—232)

This invention relates to oil wells and is more particularly concerned with improvements in systems for pumping oil from the wells.

In oil well pumping systems certain difficulties are encountered particularly in the type of oil well containing gas. One of the difficulties stems from the entrapment of gas in the pump resulting in what is known as "gas locking." If the pressure of the entrapped gases in the valve or valves of the pumping mechanism is equal to or greater than the pressure developed in the opposite direction to open the valve then the valve will remain closed and no oil will be pumped.

Accordingly, one of the objects of this invention is the provision of means for overcoming the gas locking of ordinary oil pumps, and which in use will conserve the gas and also release a portion of the bottom hole pressure in the well.

Another object of the invention is the provision of means for lightening the load on the pump without interfering with the action at any time.

A further object of the invention is the provision of a unit which can be inserted in the pipe line carrying the oil being pumped to accomplish the objects set forth above and which unit becomes an integral part of the pipe line.

A still further object of this invention is the provision of a unit which comprises a tubular section or pipe interposed in the pipe line of an oil lift, a vented shell surrounding the interposed pipe and means in the space between the shell and the interposed pipe for controlling the flow of gas to the oil being pumped through the interposed pipe in such a manner as to introduce intermittent jet action.

Other objects and advantages will appear from the following description which explains the invention in connection with an embodiment thereof illustrated in the accompanying drawing.

In the drawing:

Figure 1 is an elevational cross section of the embodiment as it appears in operative position.

Figure 2 is a section along the line 2—2 of Figure 1.

Figure 3 is a section along the line 3—3 of Figure 1.

Figure 4 is an enlarged longitudinal sectional view of one of the check valves.

Referring with more particularity to the drawing in which like numerals designate like parts, the numeral 11 identifies an ordinary well casing within which the ordinary well piping is disposed for pumping the oil out of the well. Between consecutive sections of the well piping such

as lower section 12 and an upper section 13 there is disposed the unit 14 of this invention. This unit is preferably disposed at a point about twenty feet above the bottom of the well casing and it comprises a central pipe 15 which is externally threaded at the top and bottom to engage the internal threads of couplings 16 and 17 of the adjacent pipe sections 12 and 13, respectively.

10 In spaced relation about the pipe 15 there is disposed an elongated shell 18 the upper and lower ends 19 and 20 of which are swaged to slidably engage the pipe 15 and provide an annular chamber 21 between the pipe and the shell 18. The shell is provided in two parts consisting of an upper section and a lower section which are removably secured together, such as by the threads shown in Fig. 1, to facilitate assembly and to permit the servicing and repair 20 of parts on the interior thereof.

The upper end 19 of the shell abuts the bottom of the couplings 17 and it is held in this abutting relation by means of a coil spring 22 disposed about the lower end of the pipe 15 said pipe being longer than the shell and projecting from it at either end. The lower end of the spring 22 rests on the top of the coupling 16. The upper end of the spring abuts an inner flange 23 at the top of a collar 24 surrounding the spring, said collar being secured to the lower end 20 of the shell by threads or other suitable means, such as welding. By this arrangement the coil spring tends to maintain the upper end of the shell in contact with the lower end of the coupling 17.

Within the annular chamber 21 there are disposed a plurality of tubules or ducts 25, three being shown for illustrative purposes. These ducts are preferably disposed equidistantly about the pipe 15. One end of each of the ducts 25 is welded to the pipe 15 and communicates with the interior thereof by means of vents 36 passing diagonally upward through the wall of the pipe 15. The other end of each duct 25 projects downwardly in the chamber 21 and the tip thereof is provided with an abutment bridge 27. The abutment bridge is so disposed as to leave openings 27a between it and the end of the duct.

One end of a nipple 28 is threaded on the lower end of each duct 25. The other end of the nipple has a bore 29 therethrough. At the top of the bore a check valve is provided consisting of a concave seat 30 and a ball member 31 for the seat.

55 Through the shell 18 there are provided a plu-

rality of gas vents 32. These vents preferably pass from the outside to the inside of the wall of the shell diagonally downward so that entrained solid particles in upward moving gas on the outside of the shell will tend to travel past the vents, while permitting the entrance of the gas therein.

In operation oil is pumped upward through the pipe line, including sections 12, 15 and 13. Gas escaping into the space between the pipe line and the casing 11 enters the vents 32. When the pressure of the gas is sufficiently great to overcome the weight of the balls 31 they are unseated thereby permitting the gas to flow through the bore 29 into the ducts 25 and thence into the pipe 15 through the vents 36 where oil is being pumped. The entrance of the gas under pressure into the oil line has the effect of boosting the oil upward and increasing the pressure on the intake side of the valves of the pump. This increases the efficiency of the pump and also tends to overcome any gas locking therein.

In actual practice, the action of the check valves is such as to cause the gas to enter the oil line in spurts. This action results from the elevation of the balls 31 only when the gas pressure is sufficient to overcome the weight of the balls. When this condition exists the balls are elevated and the pressure is thereby momentarily reduced causing the balls to fall back on their seats 30 and remain there until the pressure again increases sufficiently to elevate the balls. Accordingly, a continual intermittent jet action is established and maintained.

I claim:

1. An auxiliary lift comprising a pipe, a shell surrounding a portion of said pipe and being spaced therefrom to provide a chamber, said shell being swedged at the ends to slidably engage the pipe and comprising an upper section and a lower section removably secured together, couplings on the ends of said pipe, a coil spring between one coupling and the corresponding end of the shell, ducts between said shell and pipe, means communicating said ducts with the interior of said pipe, a portion of said ducts projecting downwardly and having each a check valve, said shell having vents therethrough.

2. An auxiliary lift comprising a pipe, a shell surrounding a portion of said pipe, said shell being swedged at the ends to slidably engage the pipe and provide an annular chamber therebetween, said shell comprising an upper section and a lower section removably secured together, couplings on the ends of said pipe, a coil spring between one coupling and the corresponding end of the shell, a collar surrounding said spring, said collar being secured to said shell, ducts within said annular chamber, means communicating said ducts with the interior of said pipe, a portion of said ducts projecting downwardly in said chamber and having each a check valve, said shell having vents therethrough.

3. An auxiliary lift comprising a pipe, a shell surrounding a portion of said pipe, said shell being swedged at the ends to slidably engage the pipe and provide an annular chamber therebetween, said shell comprising an upper section and a lower section removably secured together, couplings on the ends of said pipe, a coil spring between one coupling and the corresponding end of the shell, a collar surrounding said spring, said collar being secured to said shell, ducts within said annular chamber, means communicating said ducts with the interior of said pipe, a portion of said ducts projecting downwardly in said chamber, a nipple removably attached to the ends of said downwardly projecting portions and a ball check valve in each of said nipples, said shell having vents therethrough.

HORACE JUSTIN ARNALL.
